METHOD OF PRODUCING RESISTORS

Byron B. Minnium and Leland Berry, Erie, Pa.,
assignors to Erie Resistor Corporation, Erie,
Pa., a corporation of Pennsylvania

Application December 14, 1934, Serial No. 757,581

11 Claims. (Cl. 201—76)

This invention is directed to a method of making composition resistor elements whereby to produce the maximum percentage of serviceable units within the predetermined resistance limits.

5 Composition resistor elements, that is elements made of electrical conducting material with a binder or binder and filler of non-conducting material, have been made up by baking all of the units of a given group at approximately the same 0 temperature and for approximately the same length of time. After baking, the ends of the units were sprayed with metal or otherwise treated to provide low resistance terminals. The 5 units so produced were then sorted by test into groups of predetermined nominal resistance values.

Where the units were above the desired resistance value, they were sometimes resprayed or retreated at the terminals to bring them approximately to the desired value. In some cases as heretofore practiced, where one group of units 20 had been baked and found to have a too low or too high resistance value, subsequent groups of the same composition, in an attempt to produce 25 approximately the required resistance value, were baked for varying time periods, and failing to produce the desired result by these methods, it was usually necessary to change the composition and readjust it in an attempt to reach the desired 30 result.

In the conventional methods now employed, however, it has been found practically impossible to treat a group of resistor units to produce even approximately the same resistance values 35 throughout any appreciable percentage of the group, since for some unknown or undeveloped reason individual resistors of apparently the same composition respond differently to the same or similar treatments. This is well recognized and 40 attempts have been made to bring individual resistor units, after conventional treatment, to approximately the same resistance values, by subjecting them to the influence of a high frequency electrical discharge.

45 However, it is generally recognized that up to the present time all methods employed have been uniformly unsuccessful in presenting from a group of units a high percentage of completed units of approximately the same resistance values.

50 The present invention is designed particularly with a view to enabling the production of a relatively high percentage of resistor units of approximately the same resistance value from a treated group and contemplates combining with the more or less conventional baking step an automatic

sorting operation which will select during the baking operation those units which have reached approximately the desired resistance value and eject such units beyond the influence of the baking operation.

5

In considering the present method, it is to be understood that it is well known that resistor units of this character have a definite baking period in order to present in the finished unit desirable and necessary electrical properties or 10 characteristics other than the resistance value, as, for example, characteristics to meet later load and humidity conditions, and that for this reason there is a well understood minimum baking period below which the units will not present these de- 15 sired characteristics and a maximum baking period beyond which the desirable characteristics referred to would not be present. Thus, under all conditions the particular group of resistor units must be baked or heat treated at least for 20 the minimum period and cannot properly be baked or heat treated beyond the maximum period.

As the resistor units must thus be baked or heat treated for at least the minimum period, it 25 follows that the treatment, considered solely for the purpose of producing a desired resistance value, must be such as to cause the units to approach or reach this value between the minimum and maximum baking periods. That is to say, 30 the units in any event must be baked for at least the minimum period and ordinarily the baking treatment is such that at this period at least the majority of the units will not have reached the desired resistance value.

35

As the effect of the baking is to gradually reduce the resistance value of the unit and, as previously stated, the resistor units of any one group will not all respond with like effect in resistance values for the same baking period, it 40 naturally follows that during the interval between the minimum and maximum baking periods some of the resistor units will reach the desired resistance value while others will still be above that value. If the resistor units which 45 reach approximately the desired resistance value at a point intermediate the minimum and maximum baking limits are continued to be subjected to the baking influence, their resistance values will be lowered at the maximum baking period 50 beyond that desired in the particular unit.

Therefore, if the resistor units, after being subjected to the minimum baking period, are continuously thereafter, during the interval between the minimum baking period and maximum bak- 55

ing period, subjected to successive tests for resistance values and if the testing means is arranged so that the resistor units subjected to such tests are, when reaching the desired resistance value, ejected beyond the baking influence, it will be apparent that those resistor units which, if permitted to be subjected to the maximum baking period would be of a too low resistance value, are, by the process of sorting and selection, delivered with desired characteristics, both of resistance value and the other electrical characteristics noted. Thus, a comparatively large proportion of resistor units, which would otherwise be of a too low resistance value at the maximum baking period, are usefully recovered at the proper moment.

In order to provide for the ejection of the units beyond the baking influence when they have reached a predetermined resistance value, it is necessary to provide the units with low resistance ends so that the resistance may be utilized to accomplish their ejection at the particular time, and as the unit as initially constructed is not of such physical formation as to permit of the application of the low resistance ends, this result is gained by initially baking each unit to a degree to provide them with the requisite mechanical strength so that they may be handled.

Following this preliminary baking, the unit ends are sprayed or otherwise treated in any conventional or desired manner to provide the low requisite ends to enable the resistance value of the unit to be determined during the subsequent baking of it to the desired resistance.

The units so treated are placed in an oven of particular construction and subjected to a baking temperature. In order to prevent the metallic or sprayed ends of the unit from oxidizing in the oven, this baking step may be carried out in a reducing or inert atmosphere as, for example, in the presence of nitrogen, carbon dioxide or other suitable gas.

As previously stated, and in order to produce the desired electrical characteristics in a particular group of resistor units, the minimum and maximum baking periods can be readily determined and it is known that for the particular units being treated, they must be baked for at least the minimum time and should not properly be baked beyond the maximum time. As the heat treatment tends to gradually reduce the resistance values of the units, it has been demonstrated by experience that when the units have been treated for the minimum baking period, some of such units will even then be of a too low resistance value for the desired units and others, ordinarily in greater number than the first group, will not have reached a sufficiently low resistance value even when the maximum baking period has been concluded.

There is thus an interval between the minimum and maximum baking periods during which a number of resistor units will have reached the desired resistance value and if these are recovered at that particular moment, such units have the desired electrical characteristics and the requisite resistance value. If the units reaching the desired resistance value in the interval between the minimum and maximum baking periods were permitted to continue to the maximum period, their resistance value would be too low for the desired result.

In order that the matter may be better understood, it will be suggested, merely for the sake of illustration, that for a particular group of units

the minimum baking period will be 30 minutes and the maximum baking period 35 minutes. Thus, in the illustration noted, the units cannot be baked less than 30 minutes or more than 35 minutes and still retain the electrical characteristics, other than resistance values, desired. The automatic and selective sorting step commences at the limit of the minimum baking period and extends to the maximum baking period, the resistor units during this interval being subjected successively and at short intervals of time to tests for resistance values and each unit reaching the desired resistance value is ejected beyond the baking influence.

As a result of the method, the resistor units are selected and recovered as they reach the desired resistance value. Those units which, at the end of the minimum baking period, are found by the test to be of the predetermined resistance value or of a too low resistance value are ejected from the baking influence and may, of course, be later used as resistor units of a resistance value lower than that required of the particular group being treated. Those resistor units which reach the maximum baking period without selection and ejection will, of course, be of a too high resistance value for the desired group and such resistor units of a too high resistance value may be subsequently treated by respaying or retreating the terminal ends to bring them within the desired resistance value of the particular group.

The method outlined consists essentially of selecting and interrupting further heat treatment of those resistor units of a group which, following the minimum baking period, have reached the desired resistance value prior to the maximum baking period; and further, treating the resistor units of a too high resistance value following the maximum baking period to further terminal treatment to bring the resistance value to approximately that desired.

The method described can be applied to any type of resistance unit which is to be baked to the required resistance, whether such unit be of solid composition, film type, core type, or other detail. Furthermore, the method is not limited to units having sprayed or coated low resistance ends. The process is equally applicable where the unit is molded with low resistance ends or to that type of resistance in which the low resistance ends may be provided in any way inherently in the unit composition. Under those circumstances, the initial step described in connection with the above method, namely the first baking to permit handling of the unit and the subsequent application of the low resistance ends, is not necessary and the method otherwise described may be carried out with the particular type of resistance unit provided.

In carrying out the method and for a better understanding of the same, reference is had to the accompanying drawing, in which:

Figure 1 is a diagrammatic view illustrating an apparatus serviceable for carrying out the method.

Figure 2 is a broken sectional view illustrating more particularly the sorting stations.

Figure 3 is a transverse section of the same.

Figure 4 is a view in elevation showing the resistor supports by which they are individually carried by the belt or other carrier.

It is understood that the details to be described are shown with a view to illustrating an apparatus for carrying out the method. As the pres-

ent application is limited to the method and no claims made for the apparatus, applicants illustrate and describe such apparatus merely as a simple means for carrying out the method and are not to be limited in any way as to any detail of such apparatus.

As shown, 1 illustrates an oven of any desired form in which an endless carrier 2, such as a belt or the like, is arranged for travel over a predetermined path, being preferably supported on rollers 3. The interior of the oven is heated by burners 4 and the oven may be formed with an appropriate opening 5 by which the resistor units, either automatically or manually, may be supplied to the supports on the carrier.

Secured to the carrier at appropriate intervals are supporting bars 6 carrying a rigid curved arm 7 and a second similarly curved arm 8 pivotally secured at 9 to the bar 6 and influenced by a spring 10 toward the arm 7. The arm 8 has a depending lip 11 at its free end for a purpose which will later appear.

The arms 7 and 8 are of a size and shape to receive and support a resistor unit 12 and while the arm 8 is approximately semi-circular in outline, the circumferential length of the arm 7 is of less length in order to permit convenient discharge of the unit at the desired time. The supports described are duplicated adjacent the respective side edges of the carrier to thus support the resistor unit at each end and the arms 8 are connected by a strip 13 of insulating material so that such arms move in unison. Of course, but one of the arms 8 is provided with the lip 11.

The carrier, which is driven by any appropriate means (not shown), is so timed in movement that during its travel from the feeding end 5 to the point marked A will constitute the minimum baking period for the particular group of resistor units, that is the period for which the resistor units must be baked in order to present the desired electrical characteristics, other than resistance value, above referred to. The travel 45 of the carrier from the point A to the point B, the latter constituting the maximum baking period, is defined by the lower flight of the carrier and throughout this flight and immediately below the carrier are arranged rigid bars 14 and 15 arranged 50 in spaced parallelism with their relatively inner surfaces spaced apart to accurately receive and permit contact of the ends of the resistor unit 12 therewith during the travel of the unit in the movement of the carrier. Each of the bars 14 and 15 is provided at short intervals in their 55 length with contact strips 16. These contact strips are designed to be engaged by and form electrical contact with the sprayed or otherwise treated ends 17 of each resistor unit passing 60 between the bars.

Arranged below and carried by one of the bars, as 14, is a solenoid 18 for each contact strip 16. The core 19 of the solenoid is desired to be projected under energization of the solenoid into the 65 path of movement of the lip 11 of the resistor support, this core being returned to normal position by conventional spring means (not shown) on deenergization of the solenoid. A resistance meter 20 of conventional type is provided for each 70 opposed pair of contact strips 16, such meter being arranged and conventionally connected so that, when a resistor unit reaches a particular pair of contact strips, the meter, if the resistance value of the particular unit is of the desired value, 75 will energize the solenoid 18 of that particular

station, so that as the resistor unit moves in the travel of the carrier, the arms 8 of the support of that resistor unit will be moved by engagement of the projected core 19 and the lip 11 to free that resistor unit. Beneath each sorting station is arranged a hopper 21 discharging beyond the oven to a suitable receptacle, so that each resistor unit released from its support will be delivered beyond further baking influence.

No attempt is made to show any details of the 10 resistance meter, as such is entirely and purely conventional, although, of course, any preferred or desired type of control may be provided.

The initial sorting station, that is to say, the one immediately adjacent the point of minimum 15 baking influence on the resistor units, operates exactly as do the remaining sorting stations, and it will be found that at this station all resistor units which are of the desired resistance or of too low resistance value will be ejected. The remaining units travel with the carrier and are progressively brought into contact with the successive sorting stations. If at a particular station a resistor unit has a too high resistance value, the solenoid will not be affected and such particular 25 unit will move to the next station. If at this station, this resistor unit is found of the proper resistance value or slightly below such resistance value, it will be immediately ejected.

Thus, each resistor unit moving through the 30 final baking period will be subjected to a test for resistance value and if the resistance value at this test is of the proper value or slightly below such value, the unit will be ejected. Therefore, during this final baking period, all resistor units 35 which have reached the desired resistance value will be ejected beyond further baking influence and thus usefully recovered and prevented from being brought to a too low resistance value by heat treatment to a maximum period which would 40 otherwise necessarily occur. By the method and apparatus described, each resistor unit is tested successively during its travel through the particular baking period in order that, through the relatively numerous tests, the resistor units are 45 ejected when they reach the desired resistance value.

The units which, at the limit of the minimum baking period, are automatically ejected as being of a too low resistance value, may, of course, be later 50 used as units where a lower resistance value is required. Those units which reach the maximum baking period without ejection, may be subsequently treated in a conventional manner to bring at least part of them to the required value as is 55 now practiced. By the method described, a considerable proportion of resistor units passing through the oven are selected and ejected at the desired resistance value and a very considerable proportion of those which pass through the maximum baking period of a too high resistance value 60 may also be brought approximately to the desired value by conventional treatment.

What is claimed to be new is:

1. A step in the method of developing resistor units in a treatment involving baking of the units to gradually change the resistance value and develop electrical characteristics other than resistance value, consisting in subjecting the units successively to tests for resistance value during the 70 baking treatment and ejecting from the treatment zone such resistor units as have reached a predetermined resistance value.

2. A method for treating resistor units to develop resistance value and electrical character- 75

- istics other than resistance value, consisting in compelling the units to travel through a path while being subjected to a baking operation, testing each unit at a predetermined point in such path, rejecting at such point all resistor units having a resistance value equal to or less than the desired value, and thereafter and during the baking operation subjecting the remaining resistor units to successive tests for resistance value and ejecting the units at any one test which have developed the desired resistance value.
3. A method of treating resistor units to develop resistance values and load and humidity characteristics, consisting in causing the units to travel through a predetermined path while being subjected to a baking operation, with such path including a minimum baking treatment point at which the resistor units have substantially developed the load and humidity characteristics and a maximum point beyond which further baking treatment would jeopardize the load and humidity characteristics, and subjecting the units between the minimum and maximum points of baking to a selective sorting and ejection beyond the baking influence, with such selective sorting and ejection determined solely by a substantially predetermined resistance value of the unit.
4. A method as defined in claim 3, including the additional step of selecting and ejecting at the minimum point of baking all units having a resistance value equal to or less than the predetermined value.
5. A method of treating resistor units to develop in successive units a substantially predetermined resistance value, consisting in causing the units to travel through a path while being subjected to a baking operation, subjecting the units at predetermined points in such paths of travel to a test for resistance value, and ejecting those units at each period of test which have substantially reached a predetermined resistance value.
6. A method of treating resistor units for developing resistance values, consisting in causing the units to travel through a path while being subjected to a baking operation, testing the units at predetermined points in said path for resistance values, and interrupting at each point of
- test any further heat influence on those units which have reached a substantially predetermined resistance value.
7. A method of treating resistor units to develop resistance values, consisting in feeding the units progressively through a heated zone, testing each unit for resistance value at progressive points in such heat treatment, and bodily removing those units beyond further heat influence at each testing point which have reached a substantially predetermined resistance value.
8. A method of treating resistor units to develop resistance values, consisting in causing the units to travel progressively through a heated zone, and periodically testing the units and removing from such heated zone each unit which tests a predetermined resistance value.
9. A method of treating resistor units to develop resistance values, consisting in causing the units to travel in a predetermined path in the presence of a baking temperature, testing the units in succession during their travel through a final portion of said path, and ejecting those units beyond the influence of baking operation which at each testing operation indicate a substantially predetermined resistance value.
10. A method of completing resistor units, consisting in subjecting a series of units to a continuous resistance development treatment, determining the resistance value of each unit at a predetermined point in such treatment, and ejecting the units which have reached a predetermined resistance beyond the influence of the treatment while continuing the treatment of the remaining units.
11. A method of completing resistor units, consisting in subjecting a series of units successively to a resistance reducing treatment, measuring the resistance value of each unit at a predetermined point in such treatment and ejecting beyond treatment influence at such point the units which reach a predetermined resistance value while continuing the treatment of the remaining units.
